(57) **CLAIM**

We claim the ornamental design for a vacuum sealer and charger unit assembly, as shown and described.

DESCRIPTION

FIG. 1 is a perspective view of a vacuum sealer and charger unit assembly;

FIG. 2 is a top plan view of the vacuum sealer and charger unit assembly;

FIG. 3 is a front elevation view of the vacuum sealer and charger unit assembly;

FIG. 4 is a left side elevation view of the vacuum sealer and charger unit assembly;

FIG. 5 is a rear elevation view of the vacuum sealer and charger unit assembly;

FIG. 6 is a right side elevation view of the vacuum sealer and charger unit assembly;

FIG. 7 is a bottom plan view of the vacuum sealer and charger unit assembly;

FIG. 8 is a perspective view of the vacuum sealer and charger unit assembly;

FIG. 9 is a front elevation view of the vacuum sealer and charger unit assembly;

FIG. 10 is a rear elevation view of the vacuum sealer and charger unit assembly;

FIG. 11 is a left side elevation view of the vacuum sealer and charger unit assembly;

FIG. 12 is a right side elevation view of the vacuum sealer and charger unit assembly;

FIG. 13 is a bottom plan view of the vacuum sealer and charger unit assembly appliance taken along line 13-13 of FIG. 9;

FIG. 14 a top plan view of the vacuum sealer and charger unit assembly taken along line 14-14 of FIG. 9;

FIG. 15 is a bottom perspective view of the vacuum sealer and charger unit assembly; and,

FIG. 16 is a top perspective view of the vacuum sealer and charger unit assembly.

(Continued)

The broken lines shown in the drawing views illustrate portions of the vacuum sealer and charger unit assembly and form no part of the claimed design.
